UNITED STATES PATENT OFFICE.

FRANZ KRATZ AND MAX SCHÄFER, OF STUTTGART, GERMANY, ASSIGNEES, BY MESNE ASSIGNMENTS, TO AMERICAN BOSCH MAGNETO CORPORATION, OF NEW YORK, N. Y., A CORPORATION OF NEW YORK.

INTERNAL-COMBUSTION MOTOR.

1,313,090.

Specification of Letters Patent. Patented Aug. 12, 1919.

Application filed March 9, 1917. Serial No. 153,763.

To all whom it may concern:

Be it known that we, FRANZ KRATZ, a subject of the German Emperor, residing at and whose post-office address is Stuttgart, 5 Schlosstr. 59^A, Germany, and MAX SCHÄFER, a subject of the German Emperor, residing at and whose post-office address is Stuttgart, Aeussere Büchsenstr. 107, Germany, have invented certain new and useful Improvements in Internal-Combustion Motors; and we do hereby declare the following to be a full, clear, and exact description of the invention, such as will enable others skilled in the art to which it appertains to make 10 and use the same.

The present invention relates to starting apparatus for internal combustion motors, and more particularly to arrangements for preventing back fire in starting. When internal combustion motors are started with 20 a starting handle, it frequently happens that ignition occurs in the cylinder undergoing compression before the compression stroke therein is completed, thus causing an explosion before the piston passes beyond the zone 25 of possible back fire, that zone extending to the upper dead center of the piston. In consequence thereof the crank shaft is started backward with great force, and the starting handle, then coupled with the crank shaft, partakes of this sudden backward movement and may severely hurt the person cranking the motor.

There are various kinds of safety starting handles intended to obviate this defect, their construction being such that they are automatically uncoupled when the crank shaft starts to turn backward as a result of back fire. However, far greater safety is obtained if, instead of obviating the hazardous effect of the backward movement of the handle, the back fire itself is prevented. In arrangements of this kind, the operator is not affected by improper operation of the safety handle, and furthermore the motor is not damaged. The premature ignition occurring before the piston reaches its dead center, generally results from the fact that in starting the motor, the spark adjusting device is, by mistake, left in its advanced position, or in an intermediate position, instead of being set in retarded position.

The present invention obviates the hazardous effect resulting from an incorrect posi-

tion of the spark adjusting device in starting 55 the motor, and at the same time calls the operator's attention to his negligence. In accordance with the invention, whenever the period of ignition is set to other than retarded position and the starting handle is 60 coupled with the crank shaft of the motor, the ignition system is rendered ineffective to fire the engine, either by opening or short circuiting the generating winding of the ignition device at the period of ignition to 65 which the interrupter is adjusted.

In the accompanying drawings diagrammatically illustrating several embodiments of the invention, wherein, as an example, the circuit of the primary winding of a magneto is short circuited or opened whenever the period of ignition is set to other than retarded position,

Figures 1, 2, 5, 7 and 9 are plan views of several modifications; Figs. 4, 6 and 8 are 75 longitudinal cross sections of such modifications; Fig. 3 is a detail, and Fig. 10 represents another embodiment of the invention.

The screw *a* connects one terminal of the primary winding *b* of the magneto to the insulated interrupter element *c*. The co-operative deflectable interrupter element *d* is grounded. The adjustable cam ring *f* carries the deflecting cam *g*, *g*₂.

In Fig. 1, the contact segment *h* is carried 85 by the cam ring *f* but is insulated therefrom, and is connected to the screw *a* by the conductor *i*. The stationary contact spring *k* is arranged to disengage the strip *h* only when the cam ring is adjusted to retarded 90 position. The two flanges *m* of the starting handle *l* embrace a longitudinally displaceable rod *n* secured against rotation. The switch bridge *o* is carried by the rod *n* in position to bridge the studs *p* and *q* when 95 the starting handle is coupled with the engine and to disengage them when uncoupled. The stud *p* is connected to the spring *k* through the wire *r*, and the stud *q* is grounded.

The arrangement illustrated in Fig. 1 operates as follows: As long as the starting handle *l* is uncoupled from the crank shaft of the motor, the normal operation of the ignition system remains unchanged, since 105 the supplementary grounding circuit is interrupted at *p*, *q*, even though the segment *h* and spring *k* are engaged. However,

when the starting handle is coupled with the motor, the studs *p* and *q* are bridged by *o*. If, now, the cam ring *f* is in advanced or any intermediate position, the primary winding *b* of the magneto is permanently grounded by way of *a*, *i*, *h*, *k*, *r*, *p*, *o*, *q*, thus preventing the generation of an ignition voltage in the secondary winding when the interrupter elements *d*, *c* are disengaged by the cam *g*₁, *g*₂. As a result of the fact that the operator is prevented by this supplementary grounding circuit from firing the engine as long as the cam ring is set to advanced or intermediate position, his attention is called to the fact that he has neglected to adjust the period of ignition to the retarded position. On the other hand, if the interrupter is adjusted to retarded position, the supplementary grounding circuit is interrupted at *h*, *k* and the ignition system is effective for firing the engine when the starting handles is coupled with the motor.

In Figs. 2 and 3, the insulated spring *i*, fixed to the cam ring *f*, contacts with the stationary cam *z* only when the cam ring is adjusted to retarded position. At that time the spring *i* is bent out of engagement with the contact segment *h*, so that the generating winding *b* is effective for ignition, even when the starting handle is coupled with the motor. In advanced and all intermediate positions, the spring *i* is disengaged from the stationary cam *z* and therefore makes contact with the segment *h*, so that the generating winding *b* is grounded through the wire *r* when the starting handle, like in Fig. 1, is coupled with the motor.

In Fig. 4, the supplementary grounding circuit is closed by a spring and a contact segment both arranged inside the interrupter housing. The grounding switch *s* is connected in the usual way to the sleeve *u* in which the brush *t* is held in engagement with the screw *a*. The cam ring *f* is adjustably mounted on the casing of the magneto, and has a cover *v* of insulating material snugly fitted to the cam ring and having a fork *w* embracing the stationary pin 1. The flanges 2, 3 of the cam ring carry insulated oval springs 4, 5 which are connected by the wire 12 and press the contact pins 6, 7 against the contact segments 8, 9 in the cover *v*. The contact segment 8 is connected by the bar 10 to the sleeve *u*, and thence through the brush *t* to the screw *a*. The segment 9 is connected through the binding post 11 to the stud *p*. It will be observed from Fig. 5 that the contact pins 6 and 7 are so located as to be disengaged from the respective segments 8 and 9, when the cam ring is in its retarded position, and to be engaged therewith when the cam ring is in advanced or any intermediate position. Consequently, whenever the adjusting lever is in any position other than retarded position, the primary winding *b* of the magneto is short circuited through the supplementary grounding circuit whenever the starting handle is coupled with the motor.

The connection between the contacts 6, 4 and the binding post 11 might as well be effected directly through the wire 12 by employing a spiral wire adapted to elongate in the ratio of the relative movement between the cam ring *f* and the cover *v*. However, as wire connections of this kind should be avoided as far as possible in ignition devices, the second sliding contact 7, 9 is preferably employed. One of the segments 8 or 9 might be elongated sufficiently for the respective contact pins 6 or 7 to touch it in the position of advanced ignition also, since the opening and closing of the supplementary grounding circuit is controlled only by one of the two sliding contacts.

In Figs. 6 and 7, the conducting member 13 rotates with the screw *a* in electrical connection with the primary winding *b* and carries the interrupter elements *c*, *d*. Two stationary contact segments 15 and 16 are connected with each other by the wire 17 and with the binding post 11, and are of such length as to engage the brush 14 throughout the range corresponding to advanced and all positions other than retarded position. Thus when the cam ring *f* is set to retarded position, the primary winding *b* is not grounded through the supplementary grounding circuit, but when in advanced or any intermediate position, it is grounded during the period of ignition to thereby render the ignition system ineffective for firing the motor.

Figs. 8 and 9 show an arrangement in which the starting handle causes the primary winding of the magneto to be opened just previous to the period of ignition instead of short circuited, whenever, in starting the motor, the cam ring is in advanced or any position other than retarded position. The rotating member 13, which in this case is insulated from the screw *a*, carries a brush 14 co-operating with the four contact segments 18, 19, 20 and 21. The segments 18 and 19 are connected to the screw *a* by the sleeve *u* and brush *t*, and to the switch stud *p* by wire 24. The segments 20 and 21 are connected to each other by the wire 22 and to the stud *q* by wire 23. The switch bridge *o* is arranged in this case in such manner that it normally bridges the studs *p* and *q*, but disconnects them when the starting handle is coupled with the motor. When the cam ring *f* is set to retarded position, the interrupter elements *c*, *d* are disengaged by the interrupter cam when the brush 14 engages the segments 18 or 19. Just previous

- to this period of ignition, the circuit of the primary winding *b* was closed by way of *a*, *t*, *u*, 18, 19, 14, 13, *c*, *d*, and the interruption immediately following causes the generation 5 of an ignition voltage in the secondary winding of the magneto, whether or not the studs *p* and *q* were bridged by *o*. However, when the cam ring is in other than retarded position, the disengagement of the interrupter elements *c*, *d* occurs when the brush 10 14 engages the segment 21 or 20. If, in this case, the starting handle *l* is disconnected from the motor, the circuit of the primary winding *b* is closed, except at the period of 15 ignition, through *a*, *t*, *u*, 18, 24, *p*, *o*, *q*, 23, 21, 14, 13, *c*, *d*. However, if the starting handle is coupled with the motor, that circuit is open at the switch studs *p*, *q* when the interrupter elements *c*, *d* are disengaged by the 20 cams, and is closed only when the brush 14 engages the segment 18 or 19, corresponding to the retarded position of ignition. Thus, in all positions other than retarded position, the generation of ignition voltages is impossible when the starting handle *l* is coupled 25 with the motor, by reason of the fact that the primary circuit is open at the time it ought to be closed in order to build up the armature field.
- 30 In Fig. 10, the ignition in starting is generated by a starting magneto, and not by the running or service magneto. This is effected by connecting the starting magneto with the starting handle by means of special gearing, 35 and connecting the ignition circuit to the spark plugs, through the distributor of the service magneto as long as the starting handle is coupled with the crank shaft of the engine, and only during the period of retarded ignition, the service magneto being disconnected. In this arrangement, 30 is the running or service magneto, of which *b* is the primary winding, *c* the interrupter therefor, 32 the slip ring connected to the 40 secondary winding 31, and 33 a brush connected to the rotatable brush 34 of the distributor 35. The starting magneto 36 is provided with a primary winding 37, an interrupter 38, a secondary winding 39, a slip ring 40, and a stationary brush 41 connected to the rotatable brush 42 of the distributor 35. The distributor segments 43, 44, 45, 46 are connected to the spark plugs of the cylinders I, II, III and IV. The primary 45 winding *b* of the service magneto 30 is connected to the stud *p* of the switch having the bridge *o* and the grounded stud *q*. The starting handle *l* has, in addition to the coupling member 47, which is adapted to coöperate 50 with the coupling member 52 on the crank shaft of the motor, a sprocket wheel 48 adapted to drive the chain 49 and the sprocket wheel 50 which is connected through the flexible shaft 51 to the armature 55 shaft of the starting magneto 36. When it
- is desired to start the motor, the starting handle *l* is pressed in to engage the coupling members 47, 52. At the same time the bridge *o* bridges the studs *p*, *q* to short circuit the service magneto 30. When, now, the handle 70 *l* is turned, no current passes through the slip ring 32 to the distributor brush 34, but the starting magneto 36 is being driven by the flexible shaft 51 generates ignition currents which are conducted to the distributor 75 contacts 43, 44, 45, 46 through the rotating brush 42. The relative position of the brushes 34 and 42 is such that the ignition currents generated in the starting igniting device are conducted to the various spark 80 plugs in the period of retarded ignition, so that there is no danger of back fire. As soon as the starting handle is uncoupled from the motor, the studs *p*, *q* are disconnected and the starting magneto 36 comes to rest. At 85 the same time, the service magneto 30 starts to generate ignition currents which are conducted to the spark plugs of the various cylinders through the rotating distributor brush 34. 90
- The object of the present invention would be attained by controlling the secondary circuit of the igniting device instead of the primary circuit, as herein shown. However, it generally is preferable to control the 95 primary circuit, since there is less difficulty in short circuiting or interrupting the low voltage circuit.
- The same device may further be used advantageously in connection with battery 100 ignition devices. In these or other igniting devices in which the interrupter elements are stationary and the cams rotatable, the arrangements described herein must be altered only in so far as the connection of 105 the interrupter to the contact segments can be effected by stationary wires instead of carbon brushes.
- Having thus described our invention, what we claim is: 110
1. In an electric ignition system for internal combustion motors having a starting handle, a switch actuated by the starting handle, an adjustable interrupter having coöperative insulated and grounded elements, a contact segment carried by the interrupter, a brush electrically connecting the insulated element to the contact segment, and circuit connections which include the switch and the contact segment and which, when 115 the handle is coupled with the motor to crank it, render the ignition system effective to fire the motor only when the interrupter is adjusted to retarded position.
  2. In an electric ignition system for internal combustion motors having a starting handle, a switch actuated by the starting handle, a fixed contact segment, an adjustable interrupter for the ignition system, a brush carried by the rotor of the inter- 125

- rupter and coöperative with the contact segment, and circuit connections which include the switch and the contact segment and which, when the handle is coupled with the 5 motor to crank it, render the ignition system effective to fire the engine only when the interrupter is adjusted to retarded position.
3. In an electric ignition system for internal combustion motors having a starting handle, a switch actuated by the starting handle, a magneto, a fixed contact segment, an adjustable interrupter for the magneto, a brush carried by the rotor of the interrupter and coöperative with the contact segment, and circuit connections which include the switch and the contact segment and which, when the handle is coupled with the 10 motor to crank it, render the generating winding of the magneto effective to fire the engine only when the interrupter is adjusted to retarded position.
4. In an electric ignition system for internal combustion motors having a starting handle, a switch actuated by the starting handle, a magneto having primary and secondary windings, a fixed contact segment, an adjustable interrupter for the magneto, a brush carried by the rotor of the interrupter and coöperative with the contact segment, and circuit connections which include the switch and the contact segment and the primary winding of the magneto and which, when the handle is coupled with the motor to crank it, render the primary winding effective to generate a sparking voltage in the 25 secondary winding only when the interrupter is adjusted to retarded position.
5. In an electric ignition system for internal combustion motors having a starting handle, a switch actuated by the starting handle, a magneto, a fixed contact segment, an adjustable interrupter for the magneto, a brush carried by the rotor of the interrupter and coöperative with the contact segment, and circuit connections which include the switch and the contact segment and which, when the handle is coupled with the motor to crank it, render the magneto effective to fire the engine only when the interrupter is 30 adjusted to retarded position.
6. In an electric ignition system for internal combustion motors having a starting handle, a switch actuated by the starting handle, an adjustable interrupter having a contact segment and a brush arranged to engage the contact segment in all sparking positions excepting the retarded position of the interrupter, and circuit connections which include the switch and the brush and 35 the contact segment and which, when the 40 handle is coupled with the motor to crank it, render the ignition system effective to fire the engine only when the brush is disengaged from the contact segment.
7. In an electric ignition system for internal combustion motors having a starting handle, a switch actuated by the starting handle, an adjustable interrupter for the ignition system, a fixed contact segment, a brush carried by the rotor of the interrupter and arranged to engage the contact segment at all sparking positions excepting the retarded position, and circuit connections which include the switch and the brush and the contact segment and which, when the 45 handle is coupled to the motor to crank it, render the ignition system effective to fire the engine only when the brush is disengaged from the contact segment.
8. In an electric ignition system for internal combustion motors having a starting handle, a grounded switch, arranged to be closed when the starting handle is coupled with the motor and to be open when uncoupled, an adjustable interrupter having a fixed contact segment and a rotating brush arranged to engage the contact segment at all 50 sparking positions excepting the retarded position, an igniting device having a generating winding with one terminal grounded and the other terminal connected to the rotating brush, and circuit connections which include the contact segment and the switch so that when the handle is coupled with the motor to crank it, the igniting device is 55 grounded at all sparking positions excepting the retarded position.
9. In a device of the class described, in combination, an internal combustion motor, an electric ignition device operatively connected with said motor, a starting handle adapted to be temporarily coupled with the shaft of said motor, said ignition device comprising a rotary primary winding, a contact piece 14 connected to said winding, 60 counter-contact pieces 15, 16 connected to the grounding contact of said starting handle, and means for causing said contact piece 14 to come into contact with the said counter-contacts 15, 16 only when the motor piston is in the position of advanced ignition.

In testimony whereof we affix our signatures, in presence of two witnesses.
